[57] CLAIM

The ornamental design for a toothpick holder, as shown and described.

DESCRIPTION

FIG. 1 is a front elevational view of a toothpick holder showing my new design, the rear being identical;

FIG. 2 is a top plan view thereof;

FIG. 3 is a bottom plan view thereof;

FIG. 4 is a composite perspective view thereof with cap removed; and

FIG. 5 is a cross-sectional view of the toothpick holder taken along line 5—5 of FIG. 1.

FIG. 1

FIG. 2

FIG. 3

FIG. 4

FIG. 5
